UNITED STATES PATENT OFFICE.

JAMES MUSE, OF QUINCY, MASSACHUSETTS, ASSIGNOR OF ONE-THIRD TO JAMES O. BLACK, OF MALDEN, MASSACHUSETTS.

FLUID-MOTOR.

1,295,354.

Specification of Letters Patent. Patented Feb. 25, 1919.

Application filed March 12, 1918. Serial No. 222,019.

To all whom it may concern:

Be it known that I, JAMES MUSE, a subject of the Dominion of Canada, residing at Quincy, in the county of Norfolk and State 5 of Massachusetts, have invented new and useful Improvements in Fluid-Motors, of which the following is a specification.

This invention relates to a motor comprising a casing forming a circular chamber, and a wheel journaled in the casing 10 and having a circular rim and buckets projecting therefrom into the marginal portion of the chamber, and adapted to be impelled by water, or other fluid, under pressure, admitted to one portion of the chamber and 15 discharged from another portion.

The invention relates especially to the form of the internal surfaces of the casing members and of the wheel rim, and is embodied in the improved formation herein-after described and claimed adapted to confine and direct the impelling fluid in the path of some of the buckets, without appreciable leakage or divergence from said 25 path, and therefore, without loss of power, and to permit the scattering and free escape of the fluid when it reaches the end of said path, so that the rotation of the wheel is not impeded by the spent fluid.

30 Of the accompanying drawings forming a part of this specification,—

Figure 1 is an edge view of a motor embodying the invention.

Fig. 2 is a side view of the same.

35 Fig. 3 is a side view of one of the members of the casing and the wheel thereon, the other side member being removed.

Fig. 4 is a side view of the other side member, looking toward its inner side.

40 Fig. 5 is a fragmentary section on the plane of line 5—5 of Fig. 3, showing portions of both members of the casing and a portion of the wheel.

Fig. 6 is a fragmentary section similar 45 to Fig. 5, on the plane of line 6—6 of Fig. 3.

Fig. 7 is a section on line 7—7 of Fig. 4.

Fig. 8 is a section on line 8—8 of Fig. 4.

Fig. 9 is a section on line 9—9 of Figs. 2 and 3, showing one of the wheel arms or 50 spokes.

Fig. 10 represents in perspective coinciding portions of the casing members looking toward the inner sides thereof.

The same reference characters indicate the 55 same parts in all of the figures.

12 and 13 represent members of a casing forming a chamber adapted to inclose a wheel comprising a circular rim 14 and buckets 15 projecting outwardly therefrom. Each of said members includes a flat circular side or body portion forming one of the side walls of the chamber, and an inwardly projecting annular marginal flange, said flanges meeting and being bolted together, or otherwise connected to form the circular 60 marginal wall of the chamber. The body portions are provided with bearings 16 in which the wheel shaft 17 is journaled. The body portions or side walls of the casing are provided with internal fluid-confining faces 70 18, in close proximity to the lateral ends of a plurality of buckets, and with internal fluid-releasing faces 19 spaced from the lateral ends of another plurality of buckets.

The marginal portion or annular wall of 75 the casing is provided with an arcuate internal water-confining face 20, preferably formed in two sections, one on the member 12, and the other on the member 13, said sections being abutted together and forming a face 20 which is in close proximity to the outer ends of a plurality of buckets. Said annular wall is also provided with an arcuate internal fluid-releasing face 21, also 80 preferably formed in two sections, and 85 spaced from the outer ends of another plurality of buckets.

The fluid-confining faces 18 and 20 cooperate with the wheel rim 14, in forming an arcuate raceway, adapted to confine an 90 impelling fluid, and direct it in the path of a plurality of buckets, without appreciable loss of power by leakage or deviation from said path.

The casing is provided with a preferably 95 tangential fluid inlet 23 entering one end portion of said raceway. A jet of fluid is admitted through said inlet in the direction required to cause it to pass through the raceway and impel the wheel.

The water-releasing faces 19 and 21 constitute walls of an enlargement of the wheel chamber, and permit the fluid emerging from the raceway to scatter in various directions in said chamber, so that the fluid 105 after performing its function does not impede the rotation of the wheel. The spent fluid is discharged through a relatively large outlet 24 communicating with the enlarged portion of the chamber.

110

The side members of the casing are preferably provided with arcuate flanges 25, which are coextensive with and project inwardly from the fluid-confining faces 18, 5 and are in close proximity to the inner surface of the wheel rim 14, said flanges preventing or minimizing inward leakage of fluid from the said raceway, or between the edges of the wheel rim and the faces 18. 10 As shown by Fig. 9, the wheel arms or spokes 14^a are narrower than the space between the arcuate flanges 25.

Any suitable means may be provided for utilizing the rotation of the wheel through 15 the wheel shaft 17.

I claim:

1. A motor adapted to be driven by water or other fluid under pressure, and comprising a wheel having a circular rim 20 and a series of buckets projecting outwardly therefrom, a casing forming a wheel chamber and including opposed spaced apart side walls, internal fluid-confining faces in close proximity to the lateral ends 25 of the buckets, and internal fluid-releasing faces spaced from said ends, and an annular marginal wall having an arcuate in-

ternal fluid-confining face concentric with the wheel axis and in close proximity to the outer ends of the buckets, and an internal fluid-releasing face spaced from 30 said ends, said fluid-confining faces forming a contracted portion of the chamber and coöperating with the wheel rim in providing an arcuate raceway adapted to confine and direct fluid in the path of some 35 of the buckets, while said releasing faces form an enlargement of the chamber permitting fluid to scatter from the path of the remaining buckets, an inlet passage 40 communicating with one end portion of said raceway, and an outlet passage communicating with said enlargement.

2. A motor as specified by claim 1, the side walls being provided with arcuate 45 flanges projecting inwardly from the fluid-confining faces of said side walls and co-extensive therewith, said flanges being in close proximity to the inner surface of the wheel rim, and preventing or minimizing 50 inward leakage of fluid from said raceway.

In testimony whereof I have affixed my signature.

JAMES MUSE.
